CLAIM

The ornamental design for a shower filter, as shown and described.

DESCRIPTION

FIG. 1 is a perspective view of a shower filter;

FIG. 2 is a front view of the shower filter of FIG. 1;

FIG. 3 is a rear view of the shower filter of FIG. 1;

FIG. 4 is a right side view of the shower filter of FIG. 1;

FIG. 5 is a left side view of the shower filter of FIG. 1;

FIG. 6 is a top view of the shower filter of FIG. 1; and,

FIG. 7 is a bottom view of the shower filter of FIG. 1.

Any broken lines are for the purpose of illustrating portions of the shower filter that form no part of the claimed design.

1 Claim, 4 Drawing Sheets
